198,276

MACHINE FOR WASHING AUTOMOBILE FLOOR MATS AND THE LIKE

Charles W. McCarthy, 266 St. Lawrence Ave.,
Buffalo 23, N.Y.

Filed Jan. 30, 1963, Ser. No. 73,372

Term of patent 7 years

(Cl. D49—1)

FIG. 1

FIG. 2

Des. 198,276

PAGE 2

FIG. 3

FIG. 4

FIG. 5

FIG. 1 is a top plan view of a machine for washing automobile floor mats and the like, showing my new design therefor;

FIG. 2 is a rear elevational view thereof;

FIG. 3 is a front elevational view thereof;

FIG. 4 is a side elevational view thereof; and

FIG. 5 is a front perspective view thereof.

The side not shown is a mirror image of the side shown in FIG. 4.

I claim:

The ornamental design for a machine for washing automobile floor mats and the like, substantially as shown and described.
